METALLIC BEDSTEAD.

1,170,850.

Specification of Letters Patent.

Patented Feb. 8, 1916.

Application filed July 12, 1913. Serial No. 778,789.

To all whom it may concern:

Be it known that I, ERNEST L. ROSENBURGH, a citizen of the United States, residing at Rome, county of Oneida, State of New York, have invented certain new and useful Improvements in Metallic Bedsteads, the following being a full, clear, and exact disclosure of the one form of my invention which I at present deem preferable.

For a detailed description of the present form of my invention, reference may be had to the following specification and to the accompanying drawings, which illustrate my invention, wherein—

Figure 1 is an elevation of my bent frame member and Fig. 2 is a section thereof on the line $x-y$ of Fig. 1.

My invention resides in an end-frame member of a bedstead composed of a continuous length of metal tubing bent at the corners and having a double wall, to-wit, an inner wall of steel (or iron) and an outer wall of brass, the steel wall being formed of a strip bent into tubular form preferably with free abutting edges, and the brass wall being similarly formed but having its edges secured, preferably by an interlocking fold or seam contained in a shallow groove or depression in the steel tube, so that the brass wall may have a continuous circular contour unbroken by a ridge at the folded seam; such double-walled tubing I will refer to hereinafter as compound seamed tubing. In order that a compound tube of this description may be bent into a ninety degree curve to bring the vertical side-post portions at right angles to the horizontal top-rail portion of the continuous frame-member, I locate the seam of the brass tube

at a point outside of the longitudinal diameter of the tube and the seam of the steel tube I locate at a point out of the said longitudinal diameter, preferably inside thereof. By the expression longitudinal diameter I refer to a diameter from the front side to the back side of the end frame, in a direction longitudinal of the bed. By this arrangement of the seams, the stretching effect on the brass tube incident to the bending will tend to expand, instead of contract the edges of the metal adjacent to the seam and therefore prevent the buckling of the metal along the seams, while by locating the seam of the steel tube out of the said longitudinal diameter, the external pressure in-

incident to the bending will not cause the edges to fall out of line with each other between the two jaws of the bending die. In other words the meeting line of the two parts of the die will come opposite an unbroken portion of the double wall. I prefer to locate the seam of the steel within the said diameter because it is thus removed as far as possible (i. e. 180 degrees) from the seam of the brass tube. Moreover by continuing the compound tube longitudinally from each end of the curve to form the top rail on the one hand and the side-post on the other hand, I am enabled to hold the brass on the curve against bulging and splitting at the seam, such as would occur if the tube were cut off at or near one end of the curved portion. That is to say, it requires a long tangential portion on each side of the curve to keep the brass from springing away from the steel by reason of the stress in the brass on the curve.

Referring to the accompanying drawing A represents the end-frame member of my present invention, it being the fundamental member forming the rim of the end-frame to which suitable transverse members D and longitudinal members E may be secured. The member A is formed of one continuous length of compound tubing bent into shape and its complete form comprises two distinct curved portions 2-3 and 4-5, with the straight tangential portions 1-2, 3-4 and 5-6. Whatever may be the specific shape of this member A, it is important that such bent or curved portion thereof should be succeeded by a considerable length of straight or less curved portion for the purpose of retaining in place the external brass tube which would tend to bulge away from the internal steel tube on the curve but for the restraining effect of the long tangential portion, particularly at the time of the bending operation. This compound tube is of the seam type, the inner tube, which is of thicker material than the outer one, being of steel, or of iron, and the outer one of brass.

In Fig. 2 the outer tube is shown in cross section at a^1 and the inner one at a^2 . The latter has its edges meeting, but not welded together, at b^2 to produce the seam, while the former has its seam 180 degrees from b^2 at b^1 where its edges are interfolded or interlocked as shown and the overlap is seated

in a slight groove or depression b^3 in the steel tube whereby the brass tube may retain a continuous circular contour unbroken by a ridge at the fold. The horizontal 5 diameter of the compound tube in a direction longitudinal of the bed is indicated by the line $f-f$ and it will be observed that the seam b^1 lies above or outside of this diameter while the seam b^2 lies beneath or within 10 it. By this means the bending of the compound tube brings a stretching strain on the seam which tends to draw it in tightly against the inner tube, thereby preventing buckling and bulging of the outer tube 15 along the seam. On the other hand the seam b^2 does not lie in the diameter $f-f$ where it would come opposite the meeting edges of the bending dies and where the pressure of the dies would tend to force one edge of the 20 seam inward or outward with respect to the other edge and thereby cut the brass of the outer tube, but it lies out of that diametrical line and preferably within it, while the seam b^1 lies without it, so that the two seams will 25 come as far apart from each other around the tube as possible. The tubular member A is therefore one which can be produced cheaply with practically no percentage of loss in manufacturing while it also has a 30 strength and stiffness much greater than members of similar shape formed of several sections joined together. It is also stronger and far cheaper than a member formed of solid brass, since the steel affords strength 35 and rigidity while the brass tube can be very thin, so as to require only a small

amount of that expensive metal, and yet be solidly supported by the underlying steel.

What I claim as new and desire to secure by Letters Patent is:

1. A bedstead-frame member formed of a continuous length of bent compound seamed tubing.
2. A bedstead-frame member formed of a continuous length of bent compound seamed tubing each bent portion having a tangential portion adjacent thereto on each side.
3. A bedstead-frame member formed of a continuous length of bent compound seamed tubing, the seam of the external tube being outside of the longitudinal diameter thereof.
4. A bedstead-frame member formed of a continuous length of bent compound seamed tubing, the seam of the internal member being out of the longitudinal diameter thereof.
5. A bedstead-frame member formed of a continuous length of bent compound seamed tubing, the seam of the external tube being outside of and the seam of the internal tube being inside of the longitudinal diameter of the tubing.

6. An end-frame member of a bedstead having both its side-post portions and its top-rail portion formed of a continuous length of bent compound seamed tubing.

In witness whereof I have hereunto set my hand before two subscribing witnesses, this 30th day of June, 1913.

ERNEST L. ROSENBURGH.
